VANITY CASE

James L. Younghusband, Chicago, Ill.

Original application March 7, 1938, Serial No. 194,297. Divided and this application December 10, 1938, Serial No. 244,896

3 Claims. (Cl. 132—82)

This is a divisional application from the original filed on March 7, 1938, under Serial Number 194,297 for Vanity case, now Patent Number 2,147,277, Feb. 14, 1939.

5 My invention relates to a vanity case adapted to successfully hold the usual dry cosmetics such as powder or rouge and also liquid saturated cleansing pads.

10 Heretofore vanity cases have been constructed to hold only dry materials such as powder and rouge. Recently however cleansing pads saturated with liquid cleansing lotion have been introduced and immediately accepted by cosmetic users. These cleansing pads are made of thin fabric and are impregnated with liquid. They are particularly for use when the user has no other toilet facilities available. It is therefore essential that the cleansing pads be carried by the user in a container that is air and water 15 tight so as to prevent the evaporation of the liquid in the pads. A separate air and water tight vanity case for the cleansing pads involves the serious objection that the user does not care to add another vanity case to her already over- 20 crowded purse or hand bag. The ordinary vanity case already in use for dry materials such as powder and rouge is so constructed that it is neither air nor water tight. I have conducted tests by placing wet cleansing pads in the vanity cases already in use and have found that the cleansing pads not only dry out by evaporation of the liquid therein and become useless but also that the dry powder and rouge in the vanity cases absorb the liquid from the pads and 25 also become worthless for use.

30 Among the objects of this invention is to create a vanity case adapted to hold as a unit both dry materials such as powder and rouge and wet materials such as cleansing pads saturated with volatile lotion, without the one affecting the other. My vanity case has a compartment for the storage of liquid impregnated cleansing pads which is air and water tight, so as to prevent the evaporation of the liquid in the pads— 35 thus keeping them fresh and useful. My sealed compartment will also protect the dry materials from being affected and ruined by exposure to the moisture in the wet pads. My invention contemplates such other objects, advantages and capabilities as will later more fully appear and which are inherently possessed by my invention.

40 While I have disclosed herein a preferred embodiment of my invention yet I wish it understood that the same is merely illustrative and

is susceptible of modification and change without departing from the spirit of my invention.

Referring to the drawing Figs. 1, 2 and 3 are perspective views of my vanity case.

5 Referring to the embodiment selected to illustrate my invention, my vanity case comprises a pair of oppositely disposed body portions or containers 10 and 11 each having walls 12 and a base 13, said walls and base forming on their inner portions the containers. A hinge 14 attached to walls of each of said body portions 10 and 11 permits them to swing together to open and close the vanity case. One of said containers 10 is adapted to hold dry material 35 such as rouge, powder or the like. The dry material may be attached in the form of a compact to the inside base 13 of the container or it may be loose and held within the container by a powder puff, screen, door or any suitable means, the form of which we are not concerned with in this application.

10 The other container 11 is adapted to hold a plurality of liquid saturated cleansing pads 36. It is essential that a closure be provided that upon closing will seal the container 11 so that it is air and water tight. One form of said closure is a door 15 hinged to the wall 12 at one end so as to swing to open and closed position. Said door 15 has either a lining 16 covering its inner surface or a gasket 17 around its edges or rubber or the like so that when the door is closed the lining 16 or gasket 17 will compress against it and form a perfect seal on the inner walls 12 of container 11. Another means of forming the seal is to provide a member 18 of 15 rubber or the like attached to the inner walls of the container or extending from the bottom so that when the door 15 is closed it will form a perfect seal against member 18. The interior of member 18 is hollow to receive the pads 36.

20 Having thus described my invention, I claim:

1. A vanity case comprising a pair of oppositely disposed hollow body portions, hinge means attached to each of said body portions to permit them to swing to and from each other to open and closed positions, one of said body portions of sufficient depth to hold dry cosmetics, the other of said body portions of sufficient depth to hold liquid saturated pads, a door positioned between said body portions and hinged to the body portion for holding the wet pads, said door swingable on its hinge to open and close the body portion holding the wet pads, compressible material attached to that portion of the door facing the body portion holding the wet pads so 25

that as said door is moved to closed position the compressible material will compress against the inner walls of the body portion holding the wet pads and form a seal for protecting the wet pads therein from evaporation and the dry cosmetics in the other body portion from absorbing liquid from the wet pads in the body portion holding the same.

2. A vanity case comprising a pair of oppositely disposed hollow body portions, hinge means attached to each of said body portions to permit them to swing to and from each other to open and closed positions, one of said body portions of sufficient depth to hold dry cosmetics, the other of said body portions of sufficient depth to hold liquid saturated pads, a door positioned between said body portions and hinged to the body portions for holding the wet pads, said door swingable on its hinge to open and close the body portion holding the wet pads, compressible material attached to the inner walls of the body portion holding the wet pads, so that as said door is moved to closed position the door will compress the compressible material and form a seal for protecting the wet pads therein from evaporation and the dry cosmetics in the other

body portion from absorbing liquid from the wet pads in the body portion holding the same.

3. A vanity case comprising a pair of oppositely disposed hollow body portions, hinge means attached to each of said body portions to permit them to swing to and from each other to open and closed positions, one of said body portions of sufficient depth to hold dry cosmetics, the other of said body portions of sufficient depth to hold liquid saturated pads, a door positioned between said body portions and hinged to the body portion for holding the wet pads, said door swingable on its hinge to open and close the body portion holding the wet pads, compressible material attached to that portion of the door facing the body portion holding the wet pads and compressible material also attached to the inner walls of the body portion holding the wet pads, so that as said door is moved to closed position the compressible material on the door and in the body portion will be compressed by each other and form a seal for protecting the wet pads therein from evaporation and the dry cosmetics in the other body portion from absorbing liquid from the wet pads in the body portion holding the same.

JAMES L. YOUNGHUSBAND.
